UNITED STATES PATENT OFFICE

130,310

DESIGN FOR COMBINED GOGGLES AND SUPPORT THEREFOR

Percival C. Monjar, Blasdell, N. Y.

Application October 19, 1940, Serial No. 95,935

Term of patent 14 years

To all whom it may concern:

Be it known that I, Percival C. Monjar, a citizen of the United States, residing at Blasdell, in the county of Erie and State of New York, have invented a new, original, and ornamental Design for Combined Goggles and Support Therefor, of which the following is a specification, reference being had to the accompanying drawing, forming part thereof.

The figure is a perspective view of the combined goggles and support therefor showing my new design, the essential feature of which is the configuration and placement of the hangers.

I claim:

The ornamental design for combined goggles and support therefor, substantially as shown and described.

PERCIVAL C. MONJAR.
